UNITED STATES PATENT OFFICE.

LAFOREST A. SHATTUCK, OF BLOOMSBURG, PENNSYLVANIA.

CUFF-HOLDER.

SPECIFICATION forming part of Letters Patent No. 392,232, dated November 6, 1888.

Application filed June 1, 1888. Serial No. 275,712. (No model.)

To all whom it may concern:

Be it known that I, LAFOREST A. SHATTUCK, a citizen of the United States, residing at Bloomsburg, in the county of Columbia and State of Pennsylvania, have invented certain new and useful Improvements in Cuff-Retainers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention consists in a novel adjustable cuff-retainer comprising a spring-loop with a penetrating point or points, said loop being adapted for clasping and retaining the cuff against outward movement independent of the 20 coat-sleeve and of penetrating the coat-sleeve, thereby holding itself positively in position and keeping the end of the cuff and the end of the coat-sleeve in proper relative position, as will be presently described.

25 It also consists in certain novel constructions and combinations in a cuff-retainer, as will be presently described.

In the drawings, Figure 1 is a perspective view of my cuff-retainer. Fig. 2 is a similar 30 view showing a modified construction. Fig. 3 is a similar view showing another modification of the cuff-retainer. Fig. 4 is a similar view showing still another modification of the cuff-retainer, and Fig. 5 is a view of a portion 35 of a coat-sleeve and cuff with the improved cuff-retainer in its proper relation to the coat-sleeve and cuff.

The letter A in the drawings designates the cuff-retainer, which, in Figs. 1, 2, and 5, is 40 represented as constructed out of a strip of spring, plate, or sheet metal, and in Figs. 3 and 4 of round or other suitably-shaped wire. To form the retainer shown in Fig. 1, one portion of a strip of plate or sheet metal is bent 45 over upon the other, so as to form a loop for the reception or retention of a cuff, it being so bent that the portion a extends back beyond the portion b, say, for instance, about one-quarter of an inch. The said portion a is re- 50 tained in its straight or flat form along nearly its whole length; but near the point where the

bend begins it is bent in a curved form, a similar curvature being given at about the same point to the portion b, as shown at c, and thereby by a spring action secured; and rearward of 55 this curved spring portion c said portion b is deflected inward, and a roughened or file-like surface is formed on it, the deflection being preferably far enough to have it impinge against the portion a, as indicated at e, and at 60 said point the roughened or file-like surface takes a firm hold upon the cuff, and beyond this point of impingement a slightly-bowed form is imparted to the portion b, so as to increase its spring action and bring its rear end 65 in forcible bearing contact with the portion a. At the termination of the thus formed portion b a series of sharp spurs, barbs, or points for penetrating a coat-sleeve are provided on its inner side, as shown, or in any other equivalent way. In order to give increased spring 70 action to the portions a and b of the cuff-retainer, and render practicable the use of thinner or lighter plate or sheet metal in its construction, the portion b, as shown in Fig. 2, 75 may be bowed to a greater extent, and its rear end may be tapered and provided with fewer spurs, points, or barbs, and in the portion a an oblong slot or retaining depression, g, may be cut, so that a portion of the tapered end 80 with its spurs, points, or barbs may pass through the slot or into the depression. By this means a more powerful spring is obtained, as well as a longer range of movement can be secured for developing the action of said spring. 85

If desired, the cuff-retainer can be made of wire, as shown in Figs. 3 and 4, in which the rear end of the portion b can be sharpened, as at f, so as to penetrate a coat-sleeve, while the portion a may be formed of two straight horizontal strands of wire running longitudinally and connected by a horizontal loop, which is at right angles to the vertical loop c, as shown. The two wire strands give a spaced wide bearing or contact surface, and if it is desirable to 90 have this bearing or contact surface increased in width, another longitudinal wirestrand may be added, as shown in Fig. 4; and should the loop at c and the bowed form in rear of the point e not afford the requisite amount of 95 spring-force, one, two, or more helicoidal winds, as shown in Fig. 4, may be formed in 100

the portion *b* at a point between its sharp point *f* and the bend *c*, for the purpose of increasing the spring action.

It is obvious that the sharp pins might be inserted into the rear end of the portion *b*, as well as formed on it, and that the thus inserted pins would accomplish the same purpose of penetrating the coat-sleeve as the spurs, points, or barbs shown. Especially would this be practicable with the construction shown in

Fig. 2, where a slot or opening, *g*, for the passage of the point or points through the portion *a* is provided, and in some cases the spurs at the end of the portion *b*, with pins a short distance forward thereof, may be used to advantage. By providing the cuff-retainer with short spurs, points, or barbs, it, while holding itself positively on the sleeve, can be adjusted to any desired position, and thus made to keep the front edge of the cuff farther from or nearer to the edge of the sleeve, as fancy may dictate.

In using the cuff-retainer its portions *a* and *b* are sprung apart, and it is slipped upon the edge of a cuff and edge of a coat sleeve, as illustrated in Fig. 5, and then, by withdrawing the force of the fingers, it will clasp the sleeve by its spring action, which action causes both of the portions *a* and *b* to bind upon the inner surface of the cuff at *e* with a frictional hold, and at the same time the portion *b* is caused to bind upon the outer surface of the

sleeve, and its spurs, points, or barbs to penetrate the same sufficiently to insure a positive retention of the cuff-retainer and keep the cuff and sleeve in proper relation to one another.

35

The cuff-retainer may first be made of untempered metal and tempered afterward, and it also may be made of any suitable cheap metal, and afterward nickel, gold, or silver plated, or it may be made of either gold or silver.

40

What I claim as my invention is—

1. The within-described adjustable cuff-retainer, consisting of the portions *a* and *b*, connected by a bent spring portion, *c*, and provided with a penetrating point or points, *f*, on the inner surface of the portion *b*, substantially as described.

45

2. The cuff-retainer consisting of the portions *a* and *b*, connected by a bent spring portion, *c*, and provided with a penetrating point or points, *f*, on the inner side of its portion *b*, and an opening, *g*, in portion *a*, for the passage of the point or points, substantially as described.

50

In testimony whereof I affix my signature in presence of two witnesses.

LAFOREST A. SHATTUCK.
